UNITED STATES PATENT OFFICE.

AUGUST BERRER, OF FEUERBACH, GERMANY, ASSIGNOR TO FORTUNA MACHINE COMPANY, OF NEW YORK, N. Y., A CORPORATION OF NEW YORK.

SKIVING MACHINE.

Application filed September 2, 1921. Serial No. 498,093.

To all whom it may concern:

Be it known that I, AUGUST BERRER, a citizen of Germany, residing in Feuerbach, in Germany, have invented certain new and useful Improvements in Skiving Machines, of which the following is a specification, reference being had to the accompanying drawings, forming a part hereof.

This invention relates to an apparatus for leather skiving machines with revolving annular knives, and has for its object to mount the feed device, revolving within the annular knife, beneath the cutting edge, so as to swing outwardly from the housing.

By this construction the part which most hinders accessibility to the remaining parts may be easily and conveniently swung out of the way, so that then all of the remaining parts become easily accessible. At the same time the apparatus is so constructed that the swinging out of the feed device from the casing, as well as its swinging in into operative position, at all times may be easily accomplished without removing other parts of the machine, so that every interruption may be easily and quickly avoided and a thorough cleaning and repair may always be conveniently undertaken.

The exchanging of the annular knives and the grinding discs and other work in the interior of the machine may be accomplished without having to unscrew or remove the other parts.

In the drawings—

Figure 1 is a view in plan of a skiving machine having the improvements incorporated therein.

Figure 2 is a view in end elevation of the machine shown in Figure 1 with the feed device in operative relation to the revolving knife.

Figure 3 is a view similar to Figure 2 but showing the feed device swung back from the knife.

In the machine housing 1 which is an integral casting and therefore strong and capable of holding the working parts in proper relation is mounted the annular knife 2 which is driven by the driving wheel 3 and shaft 4. The machine head 5 carries as usual the pressing device 6. Laterally of the knife blade is mounted a revolving grinding disc 7, the position of which may be regulated in well known manner by a screw 8. The feeding of the leather against

the knife is brought about through a feed roll 9 which stands partly within the annular knife 2, the outer surface of the feed roll conforming substantially to the curvature of the knife. It is driven by the pulley 10 through a shaft 11 and through a bevel or worm gear mounted in the box 12, which drives the shaft 13. The latter is coupled through a readily removable connecting rod 14 (Figure 2) with the feed roller 9.

The feed roll 9 is mounted on one arm of a right angled spindle 15 which is carried by a short double-armed lever 16, and in such manner that the roller itself runs upon one arm of the spindle 15, while its other arm is rotatable in the lever 16, and has secured (so it may be adjustably fixed in position) upon its outer projecting end a bent lever 17. This lever serves to support the feed roll 9 and the leather in proper relation with the annular knife, the adjustment being accomplished on the one hand by a spring 19 which may be regulated by a screw 18, the spring being connected at its other end with the lever 16, and on the other hand through a set screw 20, which bears against the lower arm of the lever 16. The lever 16 is mounted upon a spindle 21 which is carried by a vertical carrying member 22 capable of being rocked about a vertical spindle 24 fixed in the housing 1.

By means of this arrangement it is possible to swing the entire feed device described (Figure 3) out of the housing 1 about the spindle 24. In this position of the feed device all the other parts of the machine within the housing are conveniently accessible. In the other, that is, the operative position, a stop, such as the pin 25, which bears against the housing 1, will always determine the position of the entire feed device. This will be maintained in working position through a spring 26, engaged with a pin 27, the tension of which may be regulated through a thumb nut 28. The spring 26 is connected at its free end with the hook 29, which is carried on the lower arm of the lever 16. In the same arm is threaded the set screw 30 which bears against the shoulder 23 formed in the base of the housing 1, and which screw serves to regulate the position of the feed roll 9 in so far as its distance from the knife blade is concerned. For the purpose of swinging out the feeding device it is easy to disengage the spring 26

from the hook 29 and later to re-engage it. The short rod 14 serving as a coupling piece is so constructed that it may also be easily removed and then again replaced. It will be noted that the feed roll is supported through the bent spindle 15 and the lever 17 upon an axis which is normally parallel with the axis of the knife and that the lever 16, which supports the spindle 15 and lever 17 is mounted upon a horizontal axis which is normally at right angles to the axis of the knife, and that the lever 16 is supported by the carrying member upon a vertical axis about which all parts of the feed device can be swung into and away from operative position.

I claim as my invention:

1. In a skiving machine, the combination of a housing, an annular knife, a feed roll cooperating therewith, a vertical spindle fixed in the housing, a carrying member capable of being rocked about the spindle, a lever supported by the carrying member on a horizontal axis normally at right angles to the axis of the annular knife, and a second lever mounted on the first named lever on an axis at right angles to the axis of the first named lever and supporting the feed roll.
2. In a skiving machine, the combination of a housing, an annular knife, a feed roll cooperating therewith, a vertical spindle fixed in the housing, a carrying member capable of being rocked about the housing, a lever supported by the carrying member on a horizontal axis normally at right angles to the axis of the annular knife, and a second lever mounted on the first named lever on an axis at right angles to the axis of the first named lever and supporting the feed roll, and means to hold the first named lever normally in operative position.
3. In a skiving machine, the combination of a housing, an annular knife, a feed roll cooperating therewith, a vertical spindle fixed in the housing, a carrying member capable of being rocked about the spindle, a lever supported by the carrying member on a horizontal axis normally at right angles to the axis of the annular knife, and a second lever mounted on the first named lever on an axis at right angles to the axis of the first named lever and supporting the feed roll, and a spring normally engaging the first named lever to hold the same in operative position.
4. In a skiving machine, the combination of a housing, an annular knife, a feed roll cooperating therewith, a lever supporting

the feed roll and mounted upon an axis normally parallel with the axis of the knife, and a second lever on which the first named lever is mounted and itself mounted upon a horizontal axis normally at right angles to the axis of the annular knife.

5. In a skiving machine, the combination of a housing, an annular knife, a feed roll cooperating therewith, a lever supporting the feed roll and mounted upon an axis normally parallel with the axis of the knife, and a second lever on which the first named lever is mounted and itself mounted upon a horizontal axis normally at right angles to the axis of the annular knife, and means to adjust the first named lever with respect to the second named lever.

6. In a skiving machine, the combination of a housing, an annular knife, a feed roll cooperating therewith, a lever supporting the feed roll and mounted upon an axis normally parallel with the axis of the knife, and a second lever on which the first named lever is mounted and itself mounted upon a horizontal axis normally at right angles to the axis of the annular knife, and means to hold the second named lever normally in operative position.

7. In a skiving machine, the combination of a housing, an annular knife, a feed roll cooperating therewith, a lever supporting the feed roll and mounted upon an axis normally parallel with the axis of the knife, and a second lever on which the first named lever is mounted and itself mounted upon a horizontal axis normally at right angles to the axis of the annular knife, and a spring engaging the second named lever to hold the same normally in operative position.

8. In a skiving machine, the combination of a housing, an annular knife, a feed roll cooperating therewith, a lever supporting the feed roll and mounted on an axis normally parallel with the axis of the knife, a second lever supporting the first named lever and mounted on a horizontal axis normally at right angles to the axis of the knife, a carrying member supporting the second named lever, and a vertical spindle fixed in the housing and upon which the carrying member is capable of being rocked about a vertical axis.

This specification signed this 19th day of August, A. D. 1921.

AUGUST BERRER.
